UNITED STATES PATENT OFFICE.

JAMES SHELTON, OF KNOXVILLE, TENNESSEE, ASSIGNOR OF ONE-THIRD TO JAMES J. CLARK, OF NASHVILLE, TENNESSEE.

BOILER-STUD CONNECTION.

Specification of Letters Patent.

Patented Sept. 3, 1912.

1,037,553.

Application filed July 3, 1911. Serial No. 636,652.

To all whom it may concern:

Be it known that I, JAMES SHELTON, a citizen of the United States, and a resident of the city of Knoxville, county of Knox, 5 and State of Tennessee, have invented certain new and useful Improvements in Boiler-Stud Connections, of which the following is a specification.

My invention relates to improvements in 10 studs which project from the exterior surface of steam boilers, tanks and the like, by means of which braces, brackets and other parts are secured in position.

The object of my invention is to provide 15 such a construction in a stud connection with a boiler sheet or tank as to preclude the possibility of the escape of fluid should a stud be suddenly yanked out of place, this being a common occurrence in railway and other 20 accidents.

A further object of my invention is to provide a stud connection with a boiler sheet or tank which shall be simple of construction, strong and durable, and efficient in 25 operation.

Other objects will appear hereinafter.

With these objects in view my invention consists in the combinations and arrangements of parts hereinafter described and 30 claimed.

My invention will be best understood by reference to the accompanying drawings forming a part of this specification, and in which:—

35 Figure 1 is a section of a boiler or tank sheet embodying my invention in its preferred form, Fig. 2 is a section of a boiler sheet showing a modification of my invention, Fig. 3 is a side elevation showing a 40 portion of the interior of a boiler sheet and a plate employed in the preferred form of my improved stud connection, Fig. 4 is a view similar to Fig. 3 but showing the plate employed in the modified form of stud connection, Fig. 5 is a section of a boiler sheet showing another modification of my invention, Fig. 6 is a detail side elevation showing a member employed in said last-named modified form, and Fig. 7 is a perspective 45 view showing the application of the stud connections to a locomotive boiler.

The preferred form of construction as illustrated in the accompanying drawings comprises a boiler sheet 1 having a threaded 50 aperture 2 formed therein. The axis of said

aperture is disposed transversely of the sheet so that when a threaded stud 3 is screwed into said aperture that the same will be disposed perpendicularly thereto. The threads 4 of the stud 3 are formed on one 60 end of the latter to a point sufficient to permit the threaded end of the stud to become flush with the inside of the sheet 1 when the stud is inserted. The stud 3 serves as a means for attaching a brace or bracket to 65 the exterior of the sheet 1 as will be readily understood by those skilled in the art. If no further means is provided, and should the stud 3 be accidentally wrenched from its normal position in the sheet, then fluid such 70 as steam contained within the boiler would escape freely. In order to preclude the possibility of the escape of steam in the manner above suggested and thereby to prevent scalding and other injuries a plate 5 is se- 75 cured to the interior of the sheet 1 so as to cover the threaded end of the stud 3 and the aperture into which the latter is screwed. Said plate is preferably riveted to the sheet 1 by means of a plurality of rivets 6, there 80 being a corresponding number of registering apertures formed in said plate and sheet to receive said rivets. This provision obviously is sufficient to prevent the escape of steam should the stud 3 be removed by accident or 85 otherwise.

In the modified form of stud connection shown in Figs. 2 and 4 a stud 3 is provided as in the preferred form, said stud being provided with threads 4 and screwed into a 90 threaded aperture 2. A plate 7 substantially co-extensive with the plate 5 of the preferred form is welded to the sheet 1 so as to cover the inner end of the stud 3 and the aperture into which the latter is inserted. 95 While electric welding is preferred the autogenous process may be used if desired. Dotted lines 8 in Fig. 2 indicate the line of the weld. A shallow recess 9 circular in form is preferably formed in the plate 7 so 100 as to provide clearance for the inner end of the stud 3 when screwed in position as illustrated in Fig. 2.

In the modified form of stud connection illustrated in Figs. 5 and 6 an exteriorly and interiorly threaded member 10 is provided from the center of which projects a square boss 11 designed for the reception of a wrench by means of which the member is readily screwed into the boiler sheet 1. The 110

surface of the member 10 extending from the boss 11 to the periphery of the member has a curved conformation in order to present a minimum of surface to the hot gases 5 or steam in the interior of the boiler. It is understood that the member 10 is screwed into the threaded opening in the boiler sheet 1 from the interior thereof in order that the stud 12 may be screwed into the threaded recess 13 of the member 10 from the exterior of the boiler. The stud 12 is threaded at its inner end to fit the threads of the recess 13 and at its outer end to receive a nut 14 by means of which a supporting member 15 is 15 rigidly held in position. The portion of the supporting member 15 shown in Fig. 5 may be a part of a brace 16 as shown in Fig. 7 or a part of a bracket 17 also shown in said Fig. 7. In the case of the brace 16 three 20 studs 12 may be employed if so desired. The bracket 17 may be provided with one or two studs 12 the size of the locomotive to which the brackets are applied determining this factor. A running board 18 of conventional form is shown supported by the brackets 17 in Fig. 7.

Boilers and tanks which are provided with stud connections as hereinbefore described are safer, stronger, and more efficient in operation than those in common use.

While I have illustrated and described the preferred form of construction for carrying my invention into effect, this is capable of variation and modification without departing from the spirit of the invention. I therefore do not wish to be limited to the precise details of construction as set forth, but desire to avail myself of such variations and modifications as come within the scope 40 of the appended claims.

Having described my invention what I claim as new and desire to secure by Letters Patent is:

1. In a device of the class described, the 45 combination with a boiler sheet having a threaded aperture therein, of a stud threaded at one end and screwed into said aper-

ture so as to project from one side of said sheet, and a plate secured to the other side of said sheet remote from and closing said 50 aperture, substantially as described.

2. The combination with a boiler or tank sheet, of a threaded aperture formed in said sheet, a stud threaded at one end and adapted to be screwed into said aperture so that 55 the threaded end thereof shall be flush with one side of said sheet, and a plate covering said threaded end riveted to said sheet at points remote from said aperture, substantially as described.

3. In a device of the character described, the combination with a sheet, of a threaded aperture formed in said sheet, a stud threaded at one end and screwed into said sheet, the end of said stud opposite the threaded 65 portion thereof projecting from one side of said sheet, and a plate secured to the other side of said sheet with steam and water tight connection and covering the threaded end of said stud, there being a space formed between the end of said stud and the adjacent 70 surface of said plate, substantially as described.

4. In a device of the character described, the combination with a sheet, of a threaded 75 aperture formed in said sheet, a stud threaded at one end and screwed into said sheet, the end of said stud opposite the threaded portion thereof projecting from one side of said sheet, and a plate rigidly and intimately 80 secured to the other side of said sheet, adapted to prevent leakage of steam and water under pressure between said plate and sheet and covering the threaded end of said stud, there being a space formed between said stud and the adjacent surface of said plate, substantially as described.

In testimony whereof I have signed my name to this specification in the presence of two subscribing witnesses.

JAMES SHELTON.
